UNITED STATES PATENT OFFICE.

HARRY L. KLINE, OF PORTLAND, OREGON, ASSIGNOR OF FIVE-TWENTIETHS TO FRANK C. HENDRICK AND FOUR-TWENTIETHS TO OSCAR G. LARSON, BOTH OF PORTLAND, OREGON.

ENGINE.

Application filed May 26, 1923. Serial No. 641,704.

To all whom it may concern:

Be it known that I, HARRY L. KLINE, a citizen of the United States, residing at Portland, in the county of Multnomah and 5 State of Oregon, have invented certain new and useful Improvements in Engines, of which the following is a specification, reference being had to the accompanying drawings.

10 This invention relates to certain improvements in engines and has relation more particularly to an engine embodying a plurality of pistons having rectilinear movement and it is an object of the invention to provide 15 novel and improved means whereby the reciprocation of the pistons is converted into rotary movement.

Another object of the invention is to provide an engine with novel and improved 20 means whereby the liability of a dead center is avoided.

The invention consists in the details of construction and in the combination and arrangement of the several parts of my engine 25 whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:

Figure 1 is a view partly in section and partly in top plan and somewhat of a diagrammatic character illustrating an engine constructed in accordance with an embodiment of my invention;

Figure 2 is a fragmentary view partly in section and partly in elevation illustrating a portion of my improved mechanism as herein disclosed;

45 Figure 3 is an enlarged view partly in section and partly in elevation illustrating in detail a rocking member directly engaged with the pistons together with the means associated therewith to effect the continuous rotation of the drive shaft;

50 Figure 4 is a diagrammatic view in elevation illustrating the relative arrangement of the gears as herein disclosed.

55 As disclosed in the accompanying drawings, B denotes a block herein disclosed as

provided with four cylinders 1, said cylinders being in pairs arranged at the opposite sides of the transverse center of the block. Working in the cylinders 1 are the pistons 2. The pistons 2 may receive impulse in any desired manner as by an explosive fuel, steam or otherwise. As the construction of the block and the pistons 2, in their details forms no part of my present invention I believe that a detailed disclosure is unnecessary.

Supported in desired position with respect to the pistons 2 and the point between the pairs of said pistons is a shaft 3 to one portion of which is fixed as by a key 4 or the like a sleeve 5 and loosely mounted upon said shaft 3 adjacent to the sleeve 5 is a second sleeve 6.

Loosely mounted upon the sleeves 5 and 6 is a rock member 7 provided adjacent its ends with the oppositely directed arms 8, the arms 8 at each side of said member being connected by a pin 9. Operatively engaged with each of the pins 9 are the connecting rods 10 associated with the adjacent cylinders 1 so that upon reciprocation of the pistons 2 the members 7 will be rocked or oscillated. It is to be understood that the pistons 2 of one pair are reversely related with the pistons 2 of the second pair. The member 7 in the opposite end portions thereof and at one side of its axial center is provided with the elongated cam recesses or pockets 11, said pockets being disposed in opposite directions or reversely related. Arranged within each of the recesses or pockets 11 is a clutch roller 12. One of these rollers 12 has direct coaction with the sleeve 5 while the second of said rollers 12 has direct coaction with the sleeve 6.

One end portion of the shaft 3 has fixed thereto a gear 14 which is constantly in mesh with the pinion 15 carried by a suitably positioned support 16. Movable with the pinion 15 is a gear 17 which is constantly in mesh with the gear 18 fixed to the driving shaft 19 of the engine. The shaft 19 also has fixed thereto a pinion 20 constantly in mesh with a gear 21 carried by the outer end portion of the sleeve 6.

As the pistons 2 reciprocate the member 7 rocks or oscillates with the movement of said member 7 in one direction driving or rotating the sleeve 5, and the movement in the opposite direction rotating or driving

the sleeve 6 and which reverse movements of the sleeves 5 and 6 through the instrumentality of the gears 14, 15, 17, 18, 20 and 21 result in the driving shaft 19 being continuously rotated in one direction.

Supported adjacent to the block B is a crank shaft C with which is operatively engaged a pitman 22, said pitman 22 being also operatively engaged with a pin 9 of the member 7 and preferably the pin 9 remote from the shaft C. The shaft C has fixed thereto a timer gear 23 and also a balance wheel 24. The shaft C is substantially an idle shaft although it operates to time the valve mechanism for the engine and also the ignition if said engine be of an internal combustion type. The balance wheel 24 also facilitates the operation of the engine as is believed to be clearly apparent to those skilled in the art to which the invention appertains.

As an explosion drives down one piston of the pair connected to an arm 8 or rocker as it may be termed, rotary motion is imparted to the shaft 3 by the clutch roller 12 and when the arm or rocker 8 reverses its motion, due to the explosion acting on the diagonally opposite piston in the other pair, the friction of the roller 12 with the sleeve 6 and member 7 carries the first piston of the first pair to its original position wherein the operation is repeated. In other words in the operation of the engine an explosion takes place only in one cylinder of each pair and alternately.

From the foregoing description it is thought to be obvious that an engine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting my

self to the precise arrangement and formation of the several parts herein shown in carrying out my invention in practice except as hereinafter claimed.

I claim:

1. In combination, a shaft, a sleeve loosely mounted on the shaft, a rock member mounted upon the shaft and sleeve, means for oscillating the rock member, clutching means carried by the rock member and coacting with the shaft for rotating the shaft upon movement of the rock member in one direction, second clutching means carried by the rock member and coacting with the sleeve for rotating the sleeve independently of the shaft upon movement of the rock member in the opposite direction, a driving shaft, and an operative connection between the driving shaft and the first named shaft and sleeve whereby the movements of the shaft named shaft and sleeve upon oscillation of the rock member causes the second named shaft to continuously rotate in one direction.

2. In combination, a shaft, a sleeve loosely mounted on the shaft, a rock member mounted upon the shaft and sleeve, means for oscillating the rock member, clutching means carried by the rock member and coacting with the shaft for rotating the shaft upon movement of the rock member in one direction, second clutching means carried by the rock member and coacting with the sleeve for rotating the sleeve independently of the shaft upon movement of the rock member in the opposite direction, a driving shaft, a gearing connection between the driving shaft and the first named shaft, and a gearing connection between the driving shaft and the sleeve, said gearing connections operating to rotate the driving shaft in one direction upon oscillation of the rock member.

In testimony whereof I hereunto affix my signature.

HARRY L. KLINE.
